2. Sheets-Sheet 2

Inventor

Douglas Allison

By Major Fenwick & Lawrence
Attorneys

The other clamp element comprises a jaw 46 having complementary recess 57 for cooperation with the recess 41. This jaw has a central cylindrical portion 47 which is internally threaded and arranged to engage the threaded screw 31. The insulating short-circuiting conductor 27 is secured to the flange 48 by means of set-screw 48 firmly gripping an end 49 of the conductor.

The part just described operates in the following manner: The wooden pole 30 is grasped in the hand, raising the clamp 39 into contact with one conductor of the power line and the pole 30 is then quickly rotated so as to screw the clamp member 46 into firm engagement with the line. The two clamps having firmly gripped the power line, between their jaws 41 and 57, the other portions of the device can then be utilized.

A similar clamp 29 is arranged at the upper end of the double pole device, comprising the poles 50 and 51. The clamp 29 is similarly constructed to the clamp 28 and the parts will not be re-described, but will be merely numbered with corresponding numerals each having a prime. The sleeve 31', as observed in the left-hand portion of Figure 2, is longer than the sleeve portion 31 in view of the fact that it carries a metal bracing bracket 52, which serves as well as a bearing guide 53 and 54, for the double poles. One or more clamps of this type may be placed in other spaced positions to make the poles more suitably operated. The upper clamp or brace 52 also serves as a static or other guard stopping any tendency of current to run down the pole and causing it to be conducted between the metal parts.

In the double pole construction, the bracket 40' is longer than the bracket 40, and is provided at its outer end with a hollow substantially cylindrical boss portion 55, extending downwardly into a hollow tapered skirt 56. The central aperture 58 of the boss is irregular, being broken along the diameter by the inwardly extending integral key portions 59. This construction is provided for cooperation with the remaining parts of the mechanism now to be described.

The pole 51 has a reduced portion 60 about which is secured a metallic sleeve 61, which serves as a bearing riding through the apertured end 54 of the bracket 52. The pole continues in its normal rise upwardly, and carries a conducting ring 62 provided with an outwardly extending apertured boss 63. This boss receives the other end 64 of the conductor 27, which is locked therein by set-screws 65. The ring 62 is pinned to the shaft by a pin 66, and the outer portion is tapered at 67 so as to firmly engage the inner surface 68 of the skirt. The upper end of the pole 51 is reduced in section and carries a metal cap 69 which has a downwardly extending slotted sleeve 70 pinned to the pole at 71. The slotted sleeve is arranged to receive the keys 59 and to thereby maintain the parts, during relative axial movement, in proper alignment.

The sides of the skirt 56, at right angles to the keys 59, are slotted at 73 to provide for a bayonet type connection with pin 74 carried upon the ring 62. The key and slot connections retain the parts properly aligned so that the pin 74 will be received in the entrance 75 of the slot. Each side of the slot has lower tapered seats 76 and 77 so that turning of the pole causes the pin 74 to ride to the right upon the cam seat 76, or to the left upon the cam seat 77, thereby firmly

engaging the surfaces 67 and 68 to provide a good conducting connection.

The axial movement of the pole 51 completes an electrical circuit between the conducting parts of the clamp 28 and its integral skirt 56, and 5 the parts of clamp 28 through the conductor 27 and the conducting connection thus described.

In Figure 6, a slightly different use of this device is shown, with parts corresponding to those illustrated in Figure 1 being shown with 10 similar numerals having a prime. In the use illustrated in Figure 6, the combination load clamp and ground set is shown clamped to power lines 80, 81 and 82 with the opposite ends clamped to a ground line 83 connected to ground by conductor 84. The parts are in position, but the ground connections have not been completed in the illustration since the skirts 56 have not been connected to the member 62 for the purpose of completing the circuit. The ground connection 20 will be completed, however, by the simple operation of moving the skirt and ring together.

In Figure 1, the equipment is illustrated as being used to shunt the break in the power line. If the power line is "hot," the operation 25 of the device restores the circuit around the break in an efficient manner which will allow workmen to work upon the line during the absence of a difference of potential between the points of break, which results from the restoration 30 of the circuit by the load clamp and ground set, as herein described.

In the foregoing description, the word "short-circuit" is used in its general sense to mean the formation of a relatively low resistance current 35 path about a localized relatively high resistance path which may be of infinite resistance or of lower resistance. In the use of the device as illustrated in Figure 6, it will likewise be appreciated that where the power line is carried upon 40 a metallic tower structure which is grounded, that the ground clamps can be connected directly between the power lines and the tower steel work.

With the proper operation of this device, it 45 is almost impossible for a workman to get a shock or an accidental flash burn from short-circuiting the line if it is "hot" or energized, as the contact points of the parts 62 and 56 are always open when it is initially applied, and are 50 only closed after the clamps are secured to the line, ground wire, or metal tower, as is required.

Another very valuable use for this device is in the fact that it can be used to rescue a man that has already come in contact with a line of 55 higher voltage than the rescue crew is equipped for trimming or cutting to clear the person being rescued. In such a case, by clamping the device between the two conductors and then closing the contacts, a direct short-circuit can be created 60 on the power line which would immediately trip the circuit in the sub-station or power plant, to thereby enable the workmen to free an unconscious person without subjecting the rescuers to unnecessary danger or risk.

In Figure 7 the load clamp is illustrated as having incorporated therein a fusing device to render the apparatus suitable for testing a line for short-circuits or grounds. As shown, the fuse comprises an insulating tube 86, the opposite ends of which are completed by metal members 87 and 88, being provided respectively with sleeve portions 89 encircling the tubing, and with laterally extending bosses 90. The upper member is threaded at 91 to receive a cap 92 thereon, 75

which latter is arranged to hold one end of the fuse 93 in contact with the metal member. The opposite end of the fuse extends through an aperture 94 in the metal member and is secured thereto by a screw 95. A screw 96 is arranged so that the line 27 can be secured to one end of the fuse element. The boss 90 on the upper end of the fuse, is arranged to be received within the socket 40 of the line clamp to thereby make the fuse an integral part of the entire apparatus.

After a fuse has been blown, it must be replaced. In using the present device for this purpose, branch lines are first disconnected from the main circuit, and the blown fuse replaced. The load clamp is then secured to either the main line or the feeder, and with the fuse device lighter than the main line fuse, the opposite end of the clamp is connected independently to each of the branch circuits, after which the sleeve switch 67—68 is closed to complete the circuit. As long as the feeder lines, being connected in, are clear, nothing will happen. As soon as a branch feeder, upon which trouble has developed, is connected, the fuse in the load clamp will blow before the station breakers or the main line fuse can be blown again. If the auxiliary fuse 86 blows, it would be a clear and definite indication that that portion of the circuit is in an unsafe condition, and must not be connected to the main line.

Although only a few of the advantages and uses of this device have been described for the purpose of clearly illustrating the operation and use, other advantages will be readily understood by persons skilled in the art.

Although a preferred embodiment of this invention is illustrated and described, variations within the true spirit and scope of the same are to be determined by the appended claims.

40 What I claim is:

1. Electrical ground set comprising in combination a pair of pole handled screw clamps having wire engaging jaws, a conductor connecting said screw clamps having a flexible portion, and a pole handled switch intercalated in said conductor having one of the contacts thereof rigidly supported by one of said clamps and the other contact movable with the flexible portion of said conductor.

2. Electrical ground set comprising in combination a pair of pole handled screw clamps with wire engaging jaws, a lateral arm on one of said clamps, an annular switch contact on said arm, a pole supported by said arm slideable through said contact, a complementary switch contact mounted on said pole, the latter acting as a dielectric between said contacts when said switch is open, said switch being closed by longitudinal movement of said pole relative to said annular contact, and a flexible conductor connecting the pole mounted switch contact with the other clamp.

3. Electrical ground set comprising in combination a pair of pole handled screw clamps with wire engaging jaws, a lateral arm on one of said clamps, an annular switch contact on said arm, a pole slideable through said contact, a complementary switch contact mounted on said pole, a flexible conductor connecting said pole mounted contact with said other clamp, means suspending said pole from said arm, said pole acting as a dielectric between said switch contacts when so suspended, means to prevent rotation of said pole relative to said annular contact throughout the switch closing sliding movement of said pole, and latching means between said contacts for latching said switch in closed position by partial rotation of said pole.
